UNITED STATES PATENT OFFICE.

CHARLES COCHRAN, OF MEADOW, OREGON.

RECEPTACLE.

1,114,115.

Specification of Letters Patent. Patented Oct. 20, 1914.

Application filed March 2, 1914. Serial No. 821,959.

To all whom it may concern:

Be it known that I, CHARLES COCHRAN, a citizen of the United States, residing at Meadow, in the county of Crook and State of Oregon, have invented certain new and useful Improvements in Receptacles, of which the following is a specification, reference being had to the accompanying drawings.

10 This invention relates to certain improvements in receptacles normally sealed and especially designed and adapted for use to contain a fluid substance and particularly condensed or evaporated milk; and the object of the invention is to provide novel and improved means whereby the vents produced in an end of such receptacle may be closed when not in use whereby the ingress of dirt, insects or the like is effectually prevented.

20 The invention consists in the details of construction and in the combination and arrangement of the several parts of my improved receptacle whereby certain important advantages are attained and the device is rendered simpler less expensive and otherwise more convenient and advantageous for use, all as will be hereinafter more fully set forth.

30 The novel features of the invention will be carefully defined in the appended claim.

In order that my invention may be the better understood, I will now proceed to describe the same with reference to the accompanying drawings, wherein—

35 Figure 1 is a view in top plan, with a part in section, of a receptacle constructed in accordance with an embodiment of my invention, the closure member being shown by full lines in inoperative position and indicated by dotted lines in operative position; Fig. 2 is a view in side elevation of the closure member, the coacting portions of the receptacle being indicated by dotted lines; and Fig. 3 is a top plan view of such member.

45 As disclosed in the accompanying drawings, 1 denotes a receptacle of any conventional form but herein shown as in the nature of a can generally employed to contain 50 evaporated or condensed milk or the like having produced in one of its ends or heads 2 the diametrically opposed openings 3—3,

which afford a means whereby the contents of such receptacle or can may be discharged, it being readily understood that one of such 55 openings serves as an air vent. In order to close such openings 3—3 when the device is not in use to prevent ingress within the receptacle or canal of dirt, insects or the like, I find it of particular advantage to employ 60 an elongated strip 4 of a width sufficient to entirely close the openings 3—3 and having its opposite extremities terminating in the segmental flanges 5—5 adapted to snugly 65 bear against the engaging flange 6 of the adjacent head or closure 2 whereby it will be readily perceived that such strip 4 is capable of axial rotation whereby the openings 3—3 may be uncovered when it is desired to discharge the contents of the receptacle or 70 can. While the strip 4 is capable of axial rotation, it will also be readily perceived that should the occasion so require, such strip is possessed of sufficient resiliency as to permit it being detached from the receptacle 75 or applied thereto.

From the foregoing description, it is thought to be obvious that a receptacle constructed in accordance with an embodiment of my invention is of an extremely simple 80 and comparatively inexpensive nature and is particularly well adapted for use by reason of the convenience and facility with which it performs its functions, and it will also be obvious that my invention is susceptible of 85 some change and modification without material departure from the principles and spirit thereof and for this reason I do not wish to be understood as limiting myself to the precise arrangement and formation of 90 the several parts herein shown in carrying out my invention in practice.

I claim:

In combination with a receptacle having its ends normally closed and having diametrically opposed openings produced in the peripheral portions of one of the ends, a closure member for said openings mounted upon the receptacle and capable of uninterrupted axial rotation, said member comprising 95 an elongated flat member terminating at its opposite extremities in segmental flanges adapted to snugly bear against the periphery of the receptacle, and normally 100

holding the member against movement away from the receptacle, said member having its under surface free and unobstructed, the segmental flanges of the closure member af-
5 fording the only connection with the re-
ceptacle and capable of free axial rotation relative to the receptacle.

In testimony whereof I hereunto affix my signature in the presence of two witnesses.

CHARLES COCHRAN.
